United States Patent Office

Des. 232,853
Patented Sept. 17, 1974

232,853

CRIB TOY MOBILE

Jorma Vennola, Princeton, N.J., assignor to Columbia
Broadcasting System, Inc.

Filed Feb. 16, 1973, Ser. No. 333,355

Term of patent 14 years

Int. Cl. D21—01

U.S. Cl. D34—15 J

FIG. 2

FIG. 3

FIG. 4

FIG. 1 is a side elevational view of a crib toy mobile showing my new design;

FIG. 2 is a rear elevational view thereof;

FIG. 3 is a top plan view thereof; and,

FIG. 4 is a front elevational view thereof.

I claim:

The ornamental design for a crib toy mobile, substantially as shown.
